CLAIM

The ornamental design for a toy trackway, as shown and described.

DESCRIPTION

FIG. 1 is a front perspective view of a toy trackway showing my new design;

FIG. 2 is a front elevational view thereof;

FIG. 3 is a side elevational view thereof;

FIG. 4 is a rear elevational view thereof;

FIG. 5 is a top plan view thereof;

FIG. 6 is a bottom plan view thereof; and

FIG. 7 is a cross-sectional view thereof shown partially in fragment taken along lines 6—6 of FIG. 6.

FIG. 1

FIG. 2

FIG. 3

FIG. 4

FIG. 5

FIG. 6

FIG. 7
